UNITED STATES PATENT OFFICE

2,587,673

TOGGLE-ACTUATED PIVOTED JAW
WRENCH

Clarence E. Aden, Adams, Nebr.

Application July 29, 1950, Serial No. 176,646

1 Claim. (Cl. 81—84)

1

This invention relates to improvements in toggle-actuated, pivoted jaw wrenches of a type similar to that disclosed in my previous application for a patent bearing the Serial Number 4,977, filed January 29, 1948. An object of the invention is to provide a device of the type having jaw means primarily actuated by a screw mechanism and secondarily augmented by a simple toggle lever means for increasing the holding pressure of the wrench jaws.

Another object of the invention is to provide a device of the type which will have a simple toggle mechanism coupled with the lever to increase the pressure of the grip of said jaws.

Other and further objects of the invention will appear as the description proceeds, reference being had to the accompanying drawing, in which:

Fig. 1 is a side view partly in elevation and partly in section of a wrench embodying the invention.

Fig. 2 is a fragmentary view similar to Fig. 1 showing the lever and related parts in open position.

Fig. 3 is a rear view in elevation of the wrench.

Fig. 4 is a view on line 4—4 of Fig. 2.

Fig. 5 is a view on line 5—5 of Fig. 2.

Referring more particularly to the drawing, the numeral 10 refers to the body of the wrench, having a fixed jaw 11 extending at an obtuse angle from one end thereof, and provided at its opposite end with its integral tubular portion 12 having a reduced annulus at 13 thereof. The tubular portion 12 houses an internally threaded sleeve 14 integral with a reduced portion 15 journaled in the annulus 13 and having at its outer end disposed exteriorly of the housing 12, the knurled knob 16. The internally threaded sleeve 14 is rotatable freely within the housing 12 and is in constant mesh with a threaded element 17 formed integrally with the pivot head 18 which latter is slideable longitudinally in the body 10. A handle 19 is journaled on a pin 20 held at 21 of the pivot head 18. A movable jaw 22 has the bifurcated shank portions 23 and 24 which are pivoted by means 25 and 26 to the toggle plates 27 and 28 which latter are connected by the pivot pin 29 to the lever 19. A guide pin 30 prevents lateral movement of the jaw 22 in its longitudinal travel.

A rod spring 31 has the legs 32 and 33 anchored against portion of the head 18 and with the head of its long arm 34 exerts a pressure outwardly against the movable jaw 22 between the bifurcated portions 23 and 24 of the shank thereof.

In use, the approximate desired relative positions of the jaws 11 and 22 is regulated by rotation

5 of the knob 16. The wrench is then applied to the work with the lever 19 in outwardly extended or open position as shown in Fig. 2. The lever 19 is then compressed toward the housing 12. The handle 19 will then push the pin 29 handlewise forcing the toggle plates 27 and 28 to push handlewise against the pivot members 25 and 26 thus pulling the bifurcated shank portions 23 and 24 inwardly of the body 10 and drawing the movable jaw 22 toward the fixed jaw 11 and by this means 10 tightening said jaws.

15 It will be understood that the device is capable of many modifications in structure and design, without departing from the spirit of the invention, within the scope of the appended claim.

Having thus described the invention, what is claimed and desired to be secured by Letters Patent of the United States, is:

20 A wrench comprising a body portion forming a chamber open endedly and at the back thereof, the frontal wall thereof being longitudinally slotted, a fixed jaw angularly disposed on the open end of said body portion, a tubular housing integrally formed on the opposite end of said body, 25 an internally threaded sleeve held in said tubular portion for free rotation therein, a knob integral therewith disposed exteriorly of said tubular portion for rotation of said sleeve, a pivot head movable longitudinally in said chamber, an integral screw fixed to said pivot head and in constant 30 mesh within said sleeve, a lever pivotally connected with said pivot head, a pivoted jaw held for longitudinal movement between the side walls of said chamber, a bifurcated shank integral with 35 said movable jaw, a pair of toggle plates pivotally connected within the bifurcations of said shank, and a pivotal connection at the opposite end of said toggle plates medially between the pivot point of said lever and the shank ends.
